UNITED STATES PATENT OFFICE.

GEORGE DANIEL WISELY, OF BLAIRSTOWN, MISSOURI.

LOCK.

1,261,882.

Specification of Letters Patent. Patented Apr. 9, 1918.

Application filed August 28, 1917. Serial No. 188,673.

To all whom it may concern:

Be it known that I, GEORGE DANIEL WISELY, a citizen of the United States, residing at Blairstown, in the county of Henry and State of Missouri, have invented a new and useful Lock; and I do hereby declare the following to be a full, clear, and exact description of the invention, such as will enable others skilled in the art to which it applies to make and use the same.

This invention relates to the art of locks and latches, and particularly to an improved lock, and an object of the invention is to provide a device of this kind, which is simple, efficient, and practical in construction, and may be manufactured at a small cost and sold at a reasonable profit.

A further object of the invention is to provide a gravity actuated locking bolt.

A further object of the invention is the provision of means under tension of a spring for holding the gravity actuated means of said bolt actuated.

A further object of the invention is to provide said holding means with improved means for securing said holding means out of engagement with said gravity actuated means.

In practical fields the details of construction may necessitate alterations falling within the scope of what is claimed.

The invention comprises further features and combination of parts as hereinafter set forth, shown in the drawings and claimed.

In the drawings:—

Figure 1 is a view in side elevation of the improved lock constructed in accordance with the invention.

Fig. 2 is a sectional view through the casing of the lock, showing the gravity actuated bolt and the key actuated bolt in elevation.

Fig. 3 is a sectional view on line 3—3 of Fig. 2.

Fig. 4 is a detail view of the gravity actuated holding means, showing the rib for holding said holding means out of engagement with the gravity actuating means of said bolt.

Referring more especially to the drawings, 1 designates a lock casing which may be of any suitable shape, preferably rectangular, as shown in Figs. 1, 2 and 3, and is provided with laterally extending flanges 2 having screw receiving apertures 3, to receive screws 4 to secure the casing to the door 5. Projecting from one wall of the

casing is a pair of laterally extending bars 6, which pass through the elongated slot 7 of a locking bolt 8. This bolt 8 is provided with a pair of downwardly extending spaced lugs 9. Also projecting from the wall carrying the bar 6 is a pin 10, which is designed to be telescoped by the barrel 11 of a key. This pin 10 protrudes from its wall in such a manner as to assume a position 65 between the lugs 9, so that by turning the key, the tongue 12 of the key barrel will coöperate between and with the lugs 9 for throwing the bolt 8 in one direction or the other, whereby its end 13 may engage or 70 disengage its keeper, (not shown). Guided in the guide straps 14 in the lower part of the casing 1 is a bolt 15, the usual beveled end 16 of which is adapted to automatically slide into engagement with its keeper (not 75 shown). The upper edge of the bolt 15 is provided with a series of rack teeth 17. A shaft 18 rectangular in cross section extends transversely of the casing 1. This shaft where it passes through the door 5 has a 80 cylindrical part 19. Secured by screws 20 on both ends of the shaft are the sleeves 21 of the usual door knobs 22, whereby said shaft may be rocked by either knob. A segment member 23 having teeth 24 to mesh 85 with the teeth 17 is provided. The segment member 23 has a rectangular opening 25 through which the rectangular part of the shaft 18 extends. Formed integral with the segment member where it is connected to the 90 shaft is a segment shaped weight 26, the gravitation of which actuates the segment 23, whereby the beveled end 16 of the bolt 15 is thrown into engagement with its keeper (not shown). When rocking the shaft by 95 turning either knob in the direction of the arrows *a* and *b* of Figs. 2 and 3 respectively, the weight 26 is raised, and the bolt 15 is moved out of engagement with its keeper. The casing 1 has an integral cylindrical 100 tubular auxiliary casing 27 having a flanged cover 28 threaded thereto. A pin 29 is mounted in guides 30 and 31 of the wall of the casing 1 and the cover 28. A disk 32 is carried by the pin 29, and interposed between the disk and the cover and surrounding the pin is a spring 33, to hold the inner end of the pin 29 normally in the path of the weight 26, to prevent the weight from being raised, and consequently holding the 105 bolt 15 locked. In this way the pin 29 constitutes a night latch for the bolt 15. The

pin 29 is provided with a rib 34, which, when the pin is normally in the position as shown in Fig. 2, engages a recess 35 in the wall of the guide 31. It is to be noted, 5 that by grasping the head 36 of said pin, pulling outwardly on the pin, and partially rotating or rocking the same, the inner end of said rib may engage on the outer face of the cover 28 out of alinement with the 10 recess 35, thereby holding the inner end of the pin 29 out of the path of the weight 26, as illustrated in Fig. 1 clearly, therefore, in this case the bolt 15 may be freely actuated by the shaft 18 and the weight 26. 15 When the segment weight 26 gravitates the casing at 37 will limit the segment weight in its gravitating movement. It is to be noted that segment weight 26 may be raised and the pin 29 thrown in its path, thereby 20 holding the bolt 15 retracted.

The invention having been set forth what is claimed as new and useful is:—

In a lock, a casing, a bolt having a beveled end portion penetrating through one of 25 the edge walls of the casing, a pair of arched strap guides mounted on the interior of the casing and in which said bolt is guided, said bolt having rack teeth, a knob actuated shaft extending transversely of the casing

and having a rectangular portion, a segment fitting said rectangular portion and having teeth meshing with the teeth of the rack of said bolt, a segment weight integrally carried by the first segment, whereby the beveled end portion of the bolt is held protruded beyond the edge wall of the casing, and means to be thrown in the path of the segment weight to hold the same in its gravitated position, and the bolt extended, means to limit said segment weight in its gravitated position, said first named means comprising a spring tensioned pin, a holder casing therefor, said pin having means, whereby, when the pin is withdrawn and partially rotated, said pin will be held out of the path of the segment weight, said pin when actuated by a spring and the segment weight raised, said pin will lie in the path of the segment weight and hold the bolt retracted. 35 40 45 50

In testimony whereof I have signed my name to this specification in the presence of two subscribing witnesses.

GEORGE DANIEL WISELY.
